UNITED STATES PATENT OFFICE.

MICHAEL BLANARIK, OF SOUTH NORWALK, CONNECTICUT.

CHAIR-ACTUATED BLOWER.

1,215,103.

Specification of Letters Patent.

Patented Feb. 6, 1917.

Application filed March 6, 1916. Serial No. 82,460.

To all whom it may concern:

Be it known that I, MICHAEL BLANARIK, a subject of the King of Hungary, residing at South Norwalk, in the county of Fairfield and State of Connecticut, have invented certain new and useful Improvements in Chair-Actuated Blowers, of which the following is a specification.

This invention relates to new and useful improvements in chair actuated blowers.

The primary object of the invention is the provision of an air blast mechanism adaptable for a rocking chair whereby the usual movements of the chair produces a draft of air directly upon the occupant thereof.

A further object of the device is the provision of a rocking chair having a motor driven by the oscillations of the chair whereby a fan is manipulated for producing the draft of air communicating with some desirable point upon the chair.

In carrying out these objects it is designed to provide a rocking chair of the usual form resiliently maintained in its normal rest position upon a base provided therefor, a motor driven rotary fan being carried by the chair bottom and having an air outlet tube, and the motor of the said fan being revolvable by means of pivoted operating levers having pawl and ratchet engagement with the shaft of the fan.

With these general objects in view and others that will appear as the nature of the invention is better understood, the same consists in the novel combination and arrangement of parts hereinafter fully described, illustrated in the accompanying drawings and then claimed.

In the drawings forming a part of this application and in which like designating characters refer to corresponding parts throughout the several views:—

Figure 1 is a side elevation of a chair provided with the present device and illustrated in its operative position.

Fig. 2 is a detail elevational view of one forward corner portion of the same.

Fig. 3 is a face view of the motor fan detached with the levers removed and the outlet broken away, the gears being shown diagrammatically and the fan illustrated by dotted lines.

Fig. 4 is a central transverse sectional view thereof.

55 Referring more in detail to the drawings, a rocking chair 10 is herein illustrated hav-

ing a bottom 11, side arms 12 and supporting rockers 13, the said rockers being operatively positioned within longitudinal receiving top grooves 14 of oppositely arranged stationary base members 15.

A rotary fan 16 having a propelling shaft 17 is arranged within a substantially circular casing 18 of somewhat flattened formation, the said casing being rigidly attached to and suspended from the chair bottom 11 at one side thereof by means of a bracket 19.

A ratchet wheel 20 is keyed upon the shaft 17 substantially centrally thereof and 70 relatively large and small operating gears 21 and 22 are journaled upon the shaft 17 for forcibly revolving the said ratchet 20, the said gears being arranged upon opposite sides of the ratchet 20 and in engagement therewith, the larger gear 21 being arranged between the ratchet 20 and the casing 18 while the smaller gear 22 is positioned outwardly of the ratchet 20 and retained upon the shaft 17 by means of a 75 washer 23 and a removable cotter 24.

The gear 21 is provided with a pawl 25 adapted for operatively engaging the ratchet teeth 26 of the ratchet 20 for turning the shaft 17 when the gear 21 is turned 85 in the direction indicated by the arrow in Fig. 1 of the drawings, while upon a reverse movement of the gear 21, the pawl 25 freely rides over the ratchet 20. The small gear 22 is provided with an extension 27 90 having a spring pressed pawl 28 in engagement with the ratchet teeth 26 and is arranged diametrically opposite to the pawl 25 so as to engage the teeth 26 and turn the ratchet 20 whenever the gear 22 is revolved 95 in the direction of the said arrow or in the same operative direction as heretofore described with respect to the gear 21.

A forward operating lever 29 is provided for the gear 21 having a toothed lower surface 30 engaging the teeth 31 of the said gear 21 and forcibly retained in mesh therewith by means of a helical spring 32 connecting the lever 29 with the adjacent base member 15, the said lever 29 being pivotally 100 connected to the said base member by means of a stub axle 33 positioned substantially in the plane of the adjacent forward leg 34 of the chair 10. A rear lever 35 is pivoted to a stub axle 36 carried by one of the base 105 members 15 on the outer side thereof and rearwardly of the plane of the rear legs 110.

37 of the chair. The lever 35 is provided with a toothed surface 38 upon its upper side retained in constant mesh with the small gear 22 by means of an expansion 5 spring 39 connecting the lever 35 with the adjacent base member 15.

An outlet or discharge tube 40 extends 10 from the fan casing 18 and is attached by means of a loop 41 with the adjacent chair arm 12 for directing the air blast from the fan toward the face of the occupant of the chair 10, the free end of the tube 40 preferably having a flattened nozzle 42.

From this detailed description of the complete device, the operation thereof will be apparent, it being understood that the normal position of the elements when at rest is that illustrated in Fig. 1 of the drawings, 15 positioning springs 43 being preferably arranged connecting the opposite ends of the chair rockers 13 with the base members 15. During the rocking movement of the chair 10 as influenced by the occupant thereof, the 20 downward movement of the forward portion of the chair causes the gear 21 to revolve in the direction indicated by the arrow in Fig. 1 by reason of the interengagement of the longitudinally immovable lever 29 and whereby through the agency of the pawl 25 and ratchet 20 a corresponding revolving 25 of the shaft 17 is accomplished and during which time the riding of the gear 22 upwardly upon the lever 35 allows its pawl 28 to ride freely over the ratchet 20. Upon 30 the return movement of the chair the rear portion thereof descends, thus forcing the gear 22 downwardly upon the longitudinally immovable lever 35 which results in turning the gear 22 in the said operative direction 35 and by means of its pawl 28 communicating power to the pinion 20 and fan shaft 17 and at which times the pawl 25 is idle.

It will thus be seen that during the oscillations of the chair, the levers 29 and 35 are 40 operating to propel the fan 16 substantially uninterruptedly which results in forcing an air blast through the tube 40 for the comfort of the occupant, it being designed to provide

such air blast from the usual rocking impulses imparted to the chair and without the 50 employment of additional effort ordinarily required in the fanning operation.

While the form of the invention herein shown and described is what is believed to be the preferable embodiment thereof, it is 55 nevertheless to be understood that minor changes may be made in the form, proportion and details of construction without departing from the spirit and scope of the invention as hereinafter claimed. 60

What I claim as new is:—

A device of the class described comprising base members, a rocking chair operatively positioned upon the said members, a fan casing suspendingly secured to the bottom 65 of the said chair at one side thereof, an outwardly projecting power shaft journaled in the said case, a fan secured to the said shaft within the said case, a ratchet wheel keyed to the said shaft substantially centrally of 70 the projecting portion thereof, a large gear journaled upon the said shaft between the said casing and ratchet, a pawl upon the said gear in mesh with the teeth of the said ratchet, an operating lever pivoted at its 75 lower end to the forward portion of the adjacent base member and having a toothed lower side engaging the teeth of the said gear and a compression spring connecting the said lever and the adjacent base member, a small 80 gear journaled upon the said shaft outwardly of the said ratchet, a spring pressed pawl carried by the said small gear engaging the teeth of the said ratchet at a point substantially diametrically opposite from 85 the point of engagement of the said rear gear pawl therewith, a rear operating lever pivoted to the adjacent base member at the rear portion thereof and having an upper toothed edge in mesh with the lower portion 90 of the said small gear and an expansion spring positioned between the said rear lever and the adjacent base member.

In testimony whereof I affix my signature.

MICHAEL BLANARIK.
